SUCTION CLEANER CASING

Carroll M. Gantz, North Canton, and Joseph T. Sestak, Canton, Ohio, and Robert H. Hose, Mountainside, N.J., assignors to The Hoover Company, North Canton, Ohio, a corporation of Delaware

Filed Dec. 13, 1967, Ser. No. 9,769

Term of patent 14 years

U.S. Cl. D49—14
Int. Cl. D7—06

Fig. 1

Fig. 2

Fig. 3

Fig. 4

FIGURE 1 is a top plan view of an upright suction cleaner casing, showing our new design,

FIGURE 2 is a front perspective view of the same,

FIGURE 3 is a rear elevational view, and

FIGURE 4 is a top front perspective view of the casing associated with a cleaner bag and handle shown in dotted lines.

The dominant features of our design reside in the portions shown in full lines.

We claim:

The ornamental design for a suction cleaner casing, substantially as shown and described.
